UNITED STATES PATENT OFFICE.

NAPOLEON CHARGUERAUD, OF PARIS, FRANCE.

WIRE-FEEDING MECHANISM FOR MACHINES FOR MANUFACTURING CHAIN-MAIL FABRIC.

1,176,430.

Specification of Letters Patent. Patented Mar. 21, 1916.

Application filed June 3, 1915. Serial No. 31,859.

To all whom it may concern:

Be it known that I, NAPOLEON CHARGUERAUD, a citizen of the Republic of France, residing in Paris, France, have invented certain new and useful Improvements in Wire-Feeding Mechanism for Machines for Manufacturing Chain-Mail Fabric, of which the following is a specification.

This invention has for its object a distributing or feeding device applicable to machines which serve for the manufacture of metallic fabrics of the coat-of-mail type making use of metals of several colors; and the device is destined to distribute successively and in the required manner, the metallic wires of different colors which may enter into the composition of the metallic fabric, thus forming patterns which are obtained by the fact that in each row of rings forming the fabric a certain number of rings are made of a metallic wire, for instance, of white color (silver, German silver or nickel), a further number of rings being then made of a different metallic wire, for instance red wire (gold plated wire or copper wire). The combination and operation of this particular distributing device for the manufacture of patterned fabrics of the coat-of-mail type from wires of two or more colors of different natures, will be well understood from the following description having reference to the annexed drawings.

Figure 1 is a front view of the distributing device. Fig. 2 is a plan, one of the feeding tongs being shown in section. Fig. 3 is a view seen from the left-hand side of Fig. 1. Fig. 4 is a view seen from the right-hand side of Fig. 1. Fig. 5 is a rear view of the distributing device. Fig. 6 is a transverse section on line M—M of Fig. 5. Fig. 7 is a fragmentary transverse section showing in detail one of the movable tongs; Fig. 8 is a horizontal section of the part 8 in Fig. 7; Fig. 9 is a fragmentary vertical longitudinal section through the stationary tongs, in the plane N—N Fig. 10, of one of the wires; Fig. 10 is a fragmentary horizontal section, on the line P—P in Fig. 9, being in the horizontal plane of the wires; Fig. 11 is a sectional side view of one of the levers of

the stationary tongs; Fig. 12 is an elevation of a cam wheel.

In order to enable the description of this distributing device to be easily followed and its operation to be easily understood, it will be assumed that the distributing device is to supply alternately at intervals well determined in advance and regulatable, a white metallic wire (as silver or nickel) and a red metallic wire (as gilded copper). The white wire is indicated in front on the plan, Fig. 2, and is designated by the numeral 13 while the red wire is indicated behind and designated by 13¹. The parts which relate to the two metallic wires will be indicated in this description by the same reference numerals; and those which relate to the white wire have no index while those which refer to the red wire will have the index 1.

The distributing device forming the subject of the invention comprises stationary retaining tongs seen at the left-hand side in Figs. 1 and 2; and two (or more) movable tongs. In the example shown, only two movable tongs are shown as it has been assumed that the distributing device is constructed for two metallic wires. These movable tongs produce the successive feed of the one or the other of the two metallic wires which are to serve for the formation of the coat-of-mail fabric.

The two tongs are independent, and they do not have exactly the same stroke, although the rings made from the two metals should be, and in reality are, identical; this is due to the fact that certain metals are more compressed than others by the action of the tools of the machine which form the ring pieces. The length of the hard metal which is necessary for making one ring piece, may be for instance 8 millimeters while the length of wire of the other metal may be 9 millimeters.

Each of the two movable tongs comprises a part 1 (or 1¹) carried by a slide piece 2 (or 2¹); these slides move in guide ways 3 of dove-tail section, arranged upon the rear surface of the frame of the apparatus. Each of the parts 1 (or 1¹) possesses two cheeks 4, 4 (or 4¹, 4¹), between which may move a

lever 5 (or 5¹) pivoted at 6 and so formed as to possess a pressure surface 7. Fig. 7 shows separately one of the levers 5, with the pin 8 upon which it rests; this pin 8 is shown in plan in Fig. 8. Relatively to the operative portion 7 of the lever 5, the portion 1 of the tongs carries a pin 8 which is cut out over half of its upper surface so that only half of the upper surface which is indicated by 9 may exert a pressure upon one of the two metallic wires which pass with the tongs 1 below the lever 5. The lever 5 is pressed from above by a spring 10 (or 10¹) which is interposed between said lever and a cross member 11 connecting the two cheeks 4, 4¹. Upon the end of the lever 5 is mounted a movable roller 12 the function of which will be presently explained.

The two metallic wires which serve for the formation of the fabric and which are indicated by dotted lines 13, 13¹ in Fig. 2, are guided through the feeding tongs by tubes 14, 14¹ outside the cheeks 4, 4¹. Between the cheeks of the same pair of tongs, the wires 13, 13¹ pass above the pin 8; as half of the upper surface of said pin is cut out in the manner explained above and shown in Fig. 8, only one of the two wires will be clamped between the pin 8 and the lever 5 of one pair of tongs. In the example shown in the drawings the white wire 13 is clamped and fed by the tongs shown on the right hand side of Figs. 1 and 2, or the left-hand side of Fig. 5. The other tongs situated to the left, the pin of which is shifted by half a revolution with regard to that of the tongs shown on the right-hand side of Fig. 1, is destined to feed the other metallic wire, that is the red wire 13¹.

It will now be explained in what manner the two pairs of feeding tongs are moved at the same time in the direction of the arrow 15 (Figs. 1 and 5), without however having the same length of travel. In order to allow of this difference in the length of travel which moreover is regulatable and is required for the reason previously explained, the tubes 14, 14¹ which guide the metallic wires in the tongs are not made of a single piece for the whole length of the distributing device, but are made of sections, an interval being provided between the tongs. For the same reason the tongs 1, 1¹ are carried by two separate carriages 2, 2¹.

The actuating mechanism of the tongs is operated by the lever 16, the lower end of which is provided with a roller 17 which is engaged by a cam, not shown in the drawings. The axle 18 of said lever carries (see particularly Figs. 5 and 6) an arm 19 upon which acts a spring 20 fixed at 21 to the frame 22 of the apparatus. Said arm 19 carries at its upper end a pin 23 which takes into an elongated hole or a hole of a larger

diameter 24 formed in a part 25 integral 65 with the slide 2 of the tongs 1; and said pin 23 also takes into a similar hole formed in the slide 2¹ of the other tongs 1¹. Owing to this arrangement the slides 2, 2¹ which carry the feeding tongs for the two metallic wires 70 13, 13¹ and which are returned by the springs 27, 27¹ respectively, shown in Fig. 5, may perform travels of different length according to the nature of the metallic wires which the tongs 1, 1¹ are intended to feed. The 75 extremity of the travel of the two pairs of tongs toward the left, in the direction of the arrow 15, Fig. 1, is constant; but the length of the return travel in the opposite direction may be regulated by means of the screws 80 28, 28¹ the extremities of which serve as stops for the slides 2, 2¹ respectively. As these stops determine the lengths of the metallic wires which at each stroke are supplied either by one pair of tongs or the other, for 85 feeding a length of metallic wire which is to form the blank for a ring of the coat of mail fabric, the position of these stop screws 28, 28¹ must be fixed in a very exact manner. To this end the heads 29, 29¹ of these screws 90 are provided on their peripheries with divisions, indices 30, 30¹ serving as marks for indicating the value of the return movement which may be performed by one or the other pair of feeding tongs 1, 1¹, for supplying the 95 suitable lengths of metallic wire corresponding to either of the two tongs and required for forming one ring of the fabric.

The retaining tongs which are shown on the left-hand of Fig. 1 and on the right-hand 100 side of Fig. 5, are shown separately in Fig. 9 which is a longitudinal section on N—N of Fig. 10; Fig. 10 being a horizontal section on line P—P of Fig. 9. These retaining tongs comprise a box 31 fixed to the frame 105 of the apparatus and provided with three cheeks 32, 32 and 33, between which move presser levers 34, 34¹, which coöperate with stops 35, 35¹ constituted by screws which pass through screw-threaded holes of a 110 cross-member 36. The levers 34, 34¹, one of which is separately shown in Fig. 11, make pressure contacts under the influence of lifting springs 40, 40¹ with upper stops 35, 35¹, 115 by means of the top ends of screws 37, 37¹ which may be adjusted as regards position; they are fixed in the desired position by means of set-screws 38, 38¹, while the counter-screws 35 are fixed in position by means of nuts 39, 39¹.

It will be noticed that the levers 34, 34¹ of the retaining tongs have a movement in the opposite sense to that of the levers 5 of the feeding tongs 1, 1¹, the levers 34 exerting pressure when lifted, while the levers 5 exert 125 pressure on descending.

The feeding tongs 1 of the white wire 13 which possess the pressure lever 5, and the

lever 34 of the retaining tongs are operated at the same time by a common horizontal cross member 41, while the feeding tongs 1¹ of the red wire 13¹ which are furnished with the pressure lever 5¹, and the lever 34¹ of the retaining tongs are operated at the same time by another common cross member 41¹. The two cross members 41, 41¹ are arranged one behind the other; and upon these cross members rest the rollers 12, 12¹ arranged upon the extreme ends of the levers 5, 5¹ of the feeding tongs. The member 41 is integral with a rod 42 which is guided in ways 43; this rod is lifted at its lower extremity by a cam not shown in the drawings. Upon the transverse member 41 acts a spiral spring 44 which returns the said transverse member in the downward direction. The transverse member 41¹ is also integral with a rod 42¹ arranged close to the rod 42 and lifted by the same cam as the latter rod, a spring 44¹ having always the tendency to move the transverse member 44¹ downwardly. Either the one or the other of the two transverse members 41, 41¹, but only one at a time, may rest in its upper position upon a stop which at the required moment moves from below one of the transverse members to below the other; this stop is constituted (see Fig. 1) by a finger 45 which is pivoted at 46 and is integral with an arm 47, the end of which bears against a cam 48. This cam is indicated by dotted lines in Fig. 1 and is also shown separately in view and in the same position in Fig. 12. In Fig. 1 of the drawings the end of the arm 47 is shown resting upon one of the projecting parts of the cam 48; the arm 45 is then displaced toward the left, its extreme end is therefore underneath the transverse member 41¹ which actuates, for the purpose of elevating the pressure levers, on the one hand the feeding tongs 1¹ of the red wire 13¹, and on the other hand the lever 34¹ of the retaining tongs. As soon as the extreme end of the arm 47 enters a recess of the cam 48, the arresting finger 45 is displaced from a position below the transverse member 41¹ to a position below the transverse member 41; the transverse member 41 will then remain in its upper position acting in the manner described upon the lever 5 of the feeding tongs of the white metallic wire 13 and the lever 34 of the retaining tongs.

55 The cam 48, the function of which has just been described, is integral with a ratchet wheel 49 upon which acts a pawl 50 pivoted to the upper end of the lever 16; each time when the lever 16 is operated by its cam, the pawl 50 pushes the ratchet wheel 49 by one tooth, and the cam 48 advances at the same time. So long as the arm 47 of the stop 45 rests upon the same portion, projection or recess, of the cam 48, (in Fig. 1 it is shown

resting upon a projection), the stop 45 continues to maintain the transverse member 41¹ in its upper position; but when the end of the arm 47 moves into a recess of the arm 48, the finger 45 is returned by its spring 51 and takes its position below the transverse member 41¹ so that the latter descends under the action of its spring 44¹. When the finger 45 has thus been moved toward the right, Fig. 1, its extreme end acting as a stop is below the transverse member 41 which has been raised by the cam which acts at the same time upon the two rods 42, 42¹.

15 The function of the retaining tongs is the following: When the feeding tongs recede in the direction opposite to that of the arrow 15, Figs. 1 and 5, in order to take up wire, the two levers 34, 34¹ of the retaining tongs are raised and both bear upon the metallic wires which pass through the tongs, the one 80 owing to the fact that the corresponding transverse member 41 is maintained in its raised position by the finger stop 45, the other owing to the fact that the corresponding transverse member has been raised by 90 the projection of the cam which operates the two transverse members 41, 41¹. During this action of the lifting cam, the two metallic wires are therefore clamped by the levers 85 of the retaining tongs and the feeding tongs 95 move backward to take up wire. Only that wire will be fed by its tongs, the lever of which has not been raised by its transverse member 41.

20 Between the ratchet wheel 49 and the cam 48 is arranged a disk 52 the circumference of which is formed with teeth the number of which is the same as that of the teeth of the ratchet wheel 49; into one of these teeth of the disk 52 takes a small roller 53 105 (Fig. 1) mounted upon the extreme end of an arm 54 which is raised by a small spiral spring 55; the pivoted arm 54 performs the function of a locking pawl. The disk 52 is provided upon its face, Fig. 1, with 110 numbered divisions corresponding to the teeth. These divisions have different colors, for instance white and red, and are numbered in the example shown 1, 2, 3, 4, 5, upon a segment of white color, 1, 2, 3, upon 115 a following segment of red color, and so on. The colored and numbered divisions guide the workman in his work which in the example shown is supposed to consist in the production of a fabric having five successive 120 links of white metallic wire, then three links of red wire, then five links of white wire, etc. The circular developments of these various successive sectors correspond to the circular developments of the projections and recesses of the cam 48 which operate the retaining arm 45 which maintains, 125 in its raised position, the one or the other of

the transverse members 41, 41¹ in the manner above explained.

The actuating lever 16 carries at its upper end a small elbow-lever 56 pivoted at 57, one arm of which carries a knob 58, while the extremity of the arm is formed like a fork 59 for retaining the pawl 50 by means of a pin 60; this enables the pawl 50 to be removed from the teeth of the ratchet 10 wheel so that the pawl does not act any longer upon the ratchet wheel. In this manner only one wire may be fed, either the one or the other of the two, according to the position of the arm 47, which takes into a 15 recess or bears upon a projection of the cam 48.

An index 62 fixed to the frame of the apparatus indicates exactly the divisions of the disk 52.

20 The knurled edged knob 61 which is integral with the ratchet wheel 49, the cam 48 and the toothed and numbered disk 52, enables the various members to be set in position manually when the formation of a 25 row of links has commenced; the workman knowing that for example two links of red wire are to be formed first, turns the milled edged knob in such a manner that the index 62 is placed opposite one of the members 2 of a red colored portion of the disk 62; the red wire will then be first fed at the beginning of the formation of a row so as to supply two successive links of red wire.

30 The description deals by way of example 35 with an apparatus which enables two different metallic wires to be fed; a distributing device of this kind could be also constructed so as to distribute three or more wires; it would then obviously be necessary 40 to provide as many feeding tongs as metallic wires and to multiply the pressure levers of the retaining tongs and also suitably increase the number of parts which actuate 45 the feeding tongs and the levers of the retaining tongs.

50 A distributing device of this kind may 55 obviously be used for any machine for manufacturing coat-of-mail fabrics, and particularly for the machine which forms the subject of applicant's patent application dated 23 January, 1915, No. 3,966. It would also be possible to arrange a distributing device on each side of the parts of the machine which serve for making the fabric, and this would enable the coat-of-mail fabrics to be made of a good many different metallic wires, and would enable the number of patterns to be increased.

60 It will be understood that in referring to the clamping or gripping elements as "tongs" in this specification, it is not intended to limit these to the specific construction shown, since except where otherwise specified in the claims any clamping or

gripping means is understood to be meant 65 by this term.

I claim:

1. An apparatus for feeding two wires, comprising two movable feeding tongs and two stationary retaining tongs, one of the 70 movable and one of the stationary tongs engaging one wire and the other tongs engaging the other wire, and means for opening either of the stationary tongs when the corresponding movable tongs are closed and for 75 reciprocating the movable tongs whereby to feed either wire while the other is held.

2. An apparatus for feeding two wires, comprising two movable feeding tongs and two stationary retaining tongs, the movable 80 and stationary tongs clamping the wire by opposite movements, one of the movable and one of the stationary tongs engaging one wire and the other tongs engaging the other wire, means for operating the two tongs for 85 one wire in the same direction whereby one of the tongs clamps it and the other releases it, and means for reciprocating the movable tongs.

3. An apparatus for feeding two wires, 90 comprising two movable feeding tongs and two stationary retaining tongs, each of the tongs comprising a pressure lever and an abutment, and means for forcibly opening either of the tongs for one wire while the 95 other is closed.

4. An apparatus for feeding two parallel wires, comprising two movable feeding tongs and two stationary retaining tongs, each of the tongs traversed by both wires and each 100 having a gripping portion partially cut away to clear the wire which is not to be clamped by such tongs.

5. An apparatus for feeding two wires, comprising stationary tongs and movable 105 tongs for each wire, means for opening and closing the tongs, and means for reciprocating the movable tongs adapted to move the respective movable tongs for different distances whereby a greater length of one wire 110 may be fed than of the other.

6. An apparatus for feeding two wires, comprising feeding tongs and retaining tongs for each wire, each of the tongs having a pressure lever normally closing against 115 an abutment, means for operating the tongs comprising for each wire a reciprocating part adapted to simultaneously open one of the tongs and close the other, and means for reciprocating the feeding tongs.

7. An apparatus for feeding two wires, comprising feeding tongs and retaining tongs for each wire, each of the tongs having a pressure lever normally closing against an abutment, means for operating the tongs 125 comprising for each wire a reciprocating part adapted to simultaneously open one of the tongs and close the other, and a cam op-

- erated stop adapted to arrest the tongs operating part for either wire to determine which wire shall be fed, and means for reciprocating the feeding tongs.
- 5 8. An apparatus for feeding two wires, comprising feeding tongs and retaining tongs for each wire, each of the tongs having a pressure lever normally closing against an abutment, means for operating the tongs comprising for each wire a movable member, reciprocating means for displacing both members, a movable stop for holding either member when so displaced, and a cam for moving said stop to determine which wire 15 shall be fed.
9. An apparatus for feeding two wires, comprising two movable feeding tongs and two stationary retaining tongs, one of the movable and one of the stationary 20 tongs engaging one wire and the other tongs engaging the other wire, the feeding tongs and retaining tongs opening by movements in contrary directions, means for operating the respective tongs for each 25 wire by a movement in one direction to open one tongs and in the contrary direction to open the other tongs, and means for reciprocating the movable tongs, whereby to feed either wire while the other is held.
- 30 10. An apparatus for feeding two wires, comprising two movable feeding tongs and two stationary retaining tongs, one of the movable and one of the stationary tongs engaging one wire and the other tongs engaging the other wire, the feeding tongs and retaining tongs opening by movements in contrary directions, two transverse members for actuating respectively the tongs for the respective wires, and mechanism for lifting 35 and lowering said members, and means for determining which member shall be operated and thereby determining which wire 40 shall be fed.
11. An apparatus for feeding two wires, comprising stationary tongs and movable tongs for each wire, means for opening and closing the tongs, and means for reciprocating the movable tongs adapted to move the respective movable tongs for different 45 distances whereby a greater length of one wire may be fed than of the other, comprising reciprocating means movable yieldingly in one direction and adjustable stops for limiting their movements in such direction.
- 50 12. An apparatus for feeding two wires, comprising stationary tongs and movable tongs for each wire, means for opening and closing the tongs, and means for reciprocating the movable tongs adapted to move the respective movable tongs for different 55 distances whereby a greater length of one wire may be fed than of the other, comprising slides carrying the respective movable tongs, means for reciprocating the slides, and ad-
- justable screw stops for limiting the movements of the slides in one direction.
13. An apparatus for feeding two wires, comprising movable feeding tongs and stationary retaining tongs, each of the latter comprising a fixed abutment and a pressure lever adapted to grip the wire against such abutment, with adjusting means for varying the engagement with the wire.
14. An apparatus for feeding two wires, comprising movable feeding tongs and stationary retaining tongs, each of the latter comprising a fixed abutment formed as an adjustable screw, and a pressure lever having an adjustable screw, the wire being gripped between such screws.
15. An apparatus for feeding two wires, comprising feeding tongs and retaining tongs for each wire, each of the tongs having a pressure lever normally closing against an abutment, means for operating the tongs comprising for each wire a vertically movable member, reciprocating means for lifting such members, and a movable stop for holding either member when lifted.
16. An apparatus for feeding two wires, comprising feeding tongs and retaining tongs for each wire, each of the tongs having a pressure lever normally closing against an abutment, means for operating the tongs comprising for each wire a vertically movable member, reciprocating means for simultaneously lifting both members, a movable stop for holding either member when lifted, and selective means for moving said stop to determine which member shall be upheld and which wire shall be fed.
17. An apparatus for feeding two wires, comprising feeding tongs and retaining tongs for each wire, each of the tongs having a pressure lever normally closing against an abutment, means for operating the tongs comprising for each wire a vertically movable member, reciprocating means for simultaneously lifting both members, a movable stop for holding either member when lifted, a rotary cam for operating said stop, and ratchet and pawl mechanism for turning said cam.
18. An apparatus for feeding two wires, comprising feeding tongs and retaining tongs for each wire, each of the tongs having a pressure lever normally closing against an abutment, means for operating the tongs comprising for each wire a vertically movable member, reciprocating means for simultaneously lifting both members, a movable stop for holding either member when lifted, a rotary cam for operating said stop, ratchet and pawl mechanism for turning said cam, and means for disconnecting such mechanism to permit the control of the feed by hand.
19. An apparatus for feeding two wires,

comprising feeding tongs and retaining tongs for each wire, each of the tongs having a pressure lever normally closing against an abutment, means for operating the tongs comprising for each wire a vertically movable member, reciprocating means for simultaneously lifting both members, a movable stop for holding either member when lifted, a rotary cam for supporting said stop, a 10 disk associated with said cam having indi-

cating divisions, and an index coacting with said divisions whereby to indicate which wire is to be fed.

In witness whereof, I have hereunto signed my name in the presence of two subscribing witnesses.
